UNITED STATES PATENT OFFICE.

WLADYSLAW PIJAKOWSKI, OF CHICAGO, ILLINOIS, ASSIGNOR OF SEVEN-TWENTIETHS
TO CHARLIE KAREL, OF CHICAGO, ILLINOIS.

SWIMMING DEVICE.

Application filed June 1, 1926. Serial No. 112,829.

This invention relates to swimming appliances and it has for its main object the provision of a device capable of being secured to the leg or ankle of the swimmer, and which would facilitate to make better speed.

Another object of the invention is the provision of a device comprising a pair of hinged wings which open on the backward stroke of the swimmer's legs thus affording speedy propulsion.

Another object of the invention is the provision of a device of the character stated wherein the hinged wings may be adjusted in several different positions in respect of the mounting portion of the device depending upon the particular swimming strokes used in swimming.

With the above general objects in view and others that will appear as the nature of the invention is better understood, the same consists in the novel construction, combination and arrangement of parts hereinafter more fully described, illustrated in the accompanying drawings and pointed out in the appended claims.

In the drawings forming a part of this application, and in which like designating characters refer to corresponding parts throughout the several views—

Fig. 1 illustrates the practical application of the device on swimmer's leg while the same pursues a backward stroke, with the wings open;

Fig. 2 is a side view of the device, partly in section and partly in elevation;

Fig. 3 is a top elevational view of the device while the wings remain in a closed position;

Fig. 4 is the end view of the wings and section through the fastening means of the wings, the section having been taken on line 4-4 of Fig. 3;

Fig. 5 is a side elevational view of the device illustrating another mode of adjustment of the wings in respect of the anklet band;

Fig. 6 is an end view of the device with wings mounted as in Fig. 5;

Fig. 7 is a top plan view of a portion of the device;

Fig. 8 is a top elevational view of fastening means for the wings when the same are

mounted in respect of the anklet band as illustrated on Figs. 2 and 3;

Fig. 9 is a side elevational view of the said fastening means; and

Fig. 10 is a top plan view of a portion of the device, the view being on line 10-10 of Fig. 2.

Referring to the invention in detail the same comprises an anklet band 15 made of metal or any other suitable material. Felt 16 secured to the underface of said anklet by means of stitches 17 or any other suitable means provides a protective lining so that the anklet band 15 would not come directly in contact with the body of the user. By means of straps 18 said anklet band is fastened to the leg of the swimmer. Substantially in the central portion of said anklet band a stud 19 is struck out. Bayonet slot 20 is provided centrally of said stud 19 for the purpose of receiving therewithin head 21 of screw 22 by means of which the other portions of the device hereinafter described are secured to said stud 19 and anklet band 15. As illustrated on Fig. 10 said stud has a number of depressions 23 for receiving therewithin the struck out lugs 24 made in the disk 25, by means of which arrangement said disk 25 may be held in stationary position in respect of said stud 19 and anklet band 15. At its upper face adjacent its periphery the said disk 25 is provided with serrations 26 as illustrated on Fig. 7. Positioned above said disk 25 is an oblong plate 27. Spring 28 soldered at its central portion to the underface of said plate 27 remains normally interposed between said plate 27 and disk 25. The ends of said spring 28 are also provided with serrations, which, coming in contact with serrations 26 on the disk 25 prevent movement of plate 27 in respect of disk 25. The purpose of said spring 28 is to provide cushioning means for plate 27 when under the pressure of water.

As clearly seen on Fig. 2 the end of stud 19, disk 25, spring 28 and plate 27 are held in relative stationary position by screw 22 and bolt 29.

Plate 27 at one of its ends is provided with loops 30 for the purposes hereinafter described. Portion of the material of the plate 27 remaining between said loops 30 is

formed into an upwardly projecting lip 31 for the purposes hereinafter set forth. The opposite end of said plate 27 is provided with a bayonet slot 32 for the purpose later described.

Deflecting portion of the device cooperating with portions of the device already described embodies a pair of wings 33 longitudinally hinged as at 34 on pintle 35. One 10 of the ends of said pintle 35 is provided with an integrally formed flattened head 36, and portion of said pintle 35 adjacent of the head 36 is threaded as at 37 for the purposes later mentioned. Nut 38 upon said 15 pintle 35 is adapted for operation upon said threaded portion of the pintle. The two wings 33 adjacent said head 36 and nut 38 have cutaway portions 39 for preventing the interference of said wings with the operation 20 of nut 38.

To the other end of pintle 35 moulding illustrated on Figs. 8 and 9 is mounted by screw 40. Said moulding comprises curved portion 41 fitting the periphery of pintle 35. Laterally of said portion 41 are two ears 42. Disposed below the plane of the ears 42 and in longitudinal relation therewith is loop 43, which, in the position of the wings illustrated on Figs. 1 and 3, is received between the two loops 30 of the plate 27, and 25 remains on the line with lip 31. As clearly seen on Fig. 3 loop 43 and loops 30 are in hinged relation on pin 44 which is maintained in position within the mentioned 30 loops by head 45 at one of its ends and nut 46 at the other end thereof. As illustrated on Figs. 1, 2 and 3 the two wings 33 are adapted for angular movement on their longitudinal axis on the hinged arrangement 35 comprised of loop 43 and loops 30. When the device is in use on leg of swimmer on forward stroke of the leg wings 33 will assume a parallel relation with plate 27 as indicated by dotted lines on Fig. 2. On 40 backward stroke of the leg, shown on Fig. 1, the two wings will make an angular swinging movement in the opposite direction by virtue of the pressure of water exerted upon the lower faces of the wings. In that latter case the wings will assume an upright position in respect of plate 27 as illustrated by dotted lines on Fig. 2. Further angular 45 swinging movement of the wings will be limited by lip 31 upon which the outer end 50 of curved portion 41 of the moulding of Figs. 8 and 9 will bear against. When the wings 33 remain in open position, that is the position assumed thereby on the backward stroke of the leg of the swimmer, illustrated on Fig. 1, further opening of wings 55 55 radially of pintle 35 will be limited by ears 42, as is apparent from Figs. 2 and 3. On forward stroke of the legs in addition to the angular downward movement of the 60 wings hereinafter mentioned, the wings may 65

also to some extent fold in respect to each other or make a radial swinging movement on pintle 35, but this will not be detrimental in anywise to the efficiency of the device.

Another position of the wings 33 contemplated by the present invention is illustrated on Figs. 5 and 6 whereby the wings are adjusted to remain at all times in an upright position in respect of plate 27. Such a position may be more suited to the particular strokes of a given swimmer. To adapt the wings to such position loop 43 is disconnected from loops 30 by removing nut 46 and pin 44. Portion of pintle 35 intermediate 70 between head 36 and nut 38 is inserted within bayonet slot 32 of plate 27. By tightening nut 38 upon portions of plate 27 adjacent bayonet slot 32 rigid connection of pintle 35 will be had on plate 27. When in that latter position the wings will be adapted for radial folding movement upon pintle 35, as illustrated by dotted lines on Fig. 4. Assuming that the end of plate 27 with its bayonet slot 32 is disposed toward swimmer's foot, on 75 backward stroke of the leg the wings 33 meet with resistance of water from the direction indicated by arrow on Fig. 5, the wings will open radially on pintle 35 and will thus afford considerable deflecting area 80 to enhance the swimming capacity. Further radial movement of the wings will be limited by the ears 42. On forward stroke of the swimmer's leg the wings will fold, thus facilitating the forward stroke of the leg. To 85 facilitate opening of the wings from their folded position, that is at the moment the swimmer's leg changes from forward stroke to a backward stroke a leaf spring 47 is mounted upon one of the wings by screw 90 48. Said spring prevents the complete closing of the wings on forward stroke of swimmer's leg, and maintains the wings slightly ajar in respect of each other, so that water may more readily enter between the wings 95 to open them on the backward stroke of swimmer's leg.

It is observed that in order that the wings may not interfere with the screw 40 by which moulding of Figs. 8 and 9 is 100 mounted upon pintle 35, portion of each wing adjacent said moulding and the end of pintle 35 is cut away as plainly seen on Fig. 3.

While there is described herein a preferred embodiment of the present invention, it is nevertheless to be understood that minor changes may be made therein without departing from the spirit and scope of the invention as claimed.

What I claim as new is:

1. A swimming device comprising an anklet band by means of which the device may be secured to a limb of the swimmer, a propelling member upon said anklet band,

and means upon said propelling member whereby the same may be selectively mounted upon said anklet band in several relative positions in respect to the limb of the swimmer.

2. A swimming device comprising an anklet band by means of which the device may be secured to a limb of the swimmer, a pair of hinged sections hingedly mounted upon said anklet band, said sections being adapted for making angular swinging motion axially thereof upon said anklet band, and means for alternately mounting said sections upon said anklet band adapting the sections to collapse and open on transverse plane thereof.

3. A swimming device comprising an anklet band by means of which the device may be secured to a limb of the swimmer, a

pair of hinged sections, said sections being adapted to collapse and open on transverse plane thereof, and means for alternately mounting said sections upon said anklet band for adapting the sections to make angular swinging motion axially thereof upon said anklet band.

4. A swimming device comprising an anklet band by means of which the device may be secured to a limb of the swimmer, a pair of hinged sections, and mounting means cooperating with said sections and said anklet band for alternating the relative position of said sections in respect of said anklet band.

In testimony whereof I affix my signature.

Wладислав ПИЯКОВСКИЙ.
